DESIGN FOR A BELT.

Application filed March 25, 1926. Serial No. 17,053. Term of patent 7 years.

To all whom it may concern:

Be it known that I, ISIDORE LEIBOVITZ, a citizen of the United States, and a resident of the city of New York, borough of Brooklyn, in the county of Kings and State of New York, have invented a new, original, and ornamental Design for Belt, of which the following is a specification.

Reference is to be had to the accompanying drawing in which the figure is a view in

elevation of a belt showing my new design. It is understood that this figure shows only one repeat of the belt, the further ornamentation of the belt merely being a repeat of what is shown in the drawing.

What I claim is:

The ornamental design for a belt as shown and described.

ISIDORE LEIBOVITZ.
